UNITED STATES PATENT OFFICE.

FREDERICK WILLIAM EBELING, OF NEW YORK, N. Y.

SUBMARINE DREDGING APPARATUS.

1,314,793.

Specification of Letters Patent. Patented Sept. 2, 1919.

Application filed July 1, 1918. Serial No. 242,762.

To all whom it may concern:

Be it known that I, FREDERICK W. EBELING, a citizen of the United States, residing at New York, in the county of New York 5 and State of New York, have invented certain new and useful Improvements in Submarine Dredging Apparatus, of which the following is a specification.

This invention relates to improvements in 10 submarine dredging apparatus, and seeks to provide a construction by which materials may be excavated from sunken vessels or barges, and which may be equally applicable for excavating the beds of channels or other 15 bodies of water, the construction and arrangement being such that the materials of a sunken vessel or waterbed may be more easily excavated than by dredging apparatus heretofore employed. The invention is 20 particularly applicable for salvage purposes and for placer-mining, and like operations, and is designed especially for disintegrating surfaces such as mud, sand, gravel, etc., as well as for recovering cargoes of sunken 25 vessels.

The object of the invention is to provide an apparatus for elevating materials to be recovered without the employment of special auxiliary elevating means, such as revolving 30 screws or propellers, or agitating devices which are now employed for loosening and accelerating the delivery of the substance being recovered or dredged.

The invention consists in the employment 35 of an elevating pipe having a nozzle connected at its lower end in which there are arranged annular chambers into which air, water, or steam may be conducted and employed as an elevating medium to accelerate 40 the elevation of the materials being recovered or excavated, and also, whereby air, water, or steam may be directed toward the lower end or mouth of the elevating tube or nozzle so as to displace any materials or ob- 45 jects that would tend to clog the lower end of the nozzle.

The invention still further consists in certain novel features of construction and arrangement of parts as will be hereinafter 50 fully described and then claimed.

In the accompanying drawings, illustrating the invention, in the several figures of which like parts are similarly designated, Figure 1 is a side elevation of the lower end 55 of my improved apparatus. Fig. 2 is a similar view looking at right-angles to Fig. 1.

Fig. 3 is a sectional view of the lower end of the apparatus. Fig. 4 is a plan view of the extreme lower end of the apparatus, the air inlet tubes being shown in section. Fig. 60 5 is a detail view illustrating a slightly different arrangement of construction.

1 (Figs. 1 and 2), designates the lower end of a flexible tube, such as those employed in submarine dredging apparatus, designed to 65 facilitate the manipulation of dredging tubes operated by divers. The lower end of the tube 1 is connected as by means of a suitable coupling 2 with a pipe 3 having its lower end threaded, as at 4, to receive a 70 coupling ring 5, which is designed to lock a nozzle 6 to the extreme lower end of the pipe 3, the construction and arrangement being such that the several parts may be 75 readily disconnected in order to make various repairs as is often necessary in apparatus of this kind.

Within the lower end of the nozzle 6 there is arranged a sleeve 7 of less diameter than the nozzle 6, the said sleeve being supported 80 within and held fast to the lower end of the nozzle by means of rings 8, which are held in place by rivets 9, as shown in Fig. 3; and between these rings 8 there is interposed a suitable packing 10, such as Babbitt metal 85 or other suitable substance, so as to provide an air-tight joint between the upper and lower ends 11 and 12, respectively, of the sleeve 7 formed by the rings 8. This construction provides annular chambers at and 90 between the upper and lower ends of the sleeve 7 and the elevating pipe 3. Arranged both at the upper and lower ends of the sleeve 7 are rings 13, having their inner faces beveled as at 14, whereby to provide 95 a channel 15 between the annular spaces and the upper and lower ends, respectively, of the sleeve 7, and having an outlet so as to accelerate the materials being elevated.

In practice the rings 13 are riveted to the 100 nozzle 6, but, as shown in Fig. 5, I may thread the upper and lower ends of the nozzle 6 so that the rings 13 may be adjusted in order to increase or decrease the size of the openings between the upper and 105 lower ends of the sleeve 7. It will be understood, of course, that the rings 13 will be provided with sockets to receive suitable tools for adjusting the rings whereby to elevate or lower them so as to increase or 110 decrease the annular orifice at the respective ends of the sleeve 7.

The nozzle 6 is provided with openings 16 and 17, which are surrounded by suitably connected collars 18 having short sleeves 19 threaded therein to which are 5 connected elbows 20 having their outer ends threaded to receive conducting pipes 21 and 21', the upper ends of said pipes being provided with couplings 23 (Figs. 1 and 2), to receive flexible pipes 24, extending from 10 a suitable air or water pump (not shown), or from an air receiving tank (not shown), arranged upon a surface vessel co-acting with the apparatus. As shown in Figs. 1 and 2, the pipes 21 and 21' are connected 15 by suitable brackets 25 located adjacent to the upper end of the pipe 3, and are coupled adjacent to their lower ends as at 25' so as to facilitate the disconnection of the pipe 3 from the nozzle 6, whereby to permit the 20 adjustment of the ring 13 at the upper end of the sleeve, so as to provide a greater or less outlet at the upper end of the sleeve 7, necessary in the employment of air or water as an elevating medium.

25 As before stated, the invention is designed for excavating materials by means of air, water, or steam, so as to elevate the materials being operated upon and to thus force the material up through the delivery 30 pipe 1. In practice the pipes 21 and 21' are preferably connected to a compressed air receiving tank, or to a force pump, or to a steam dome (not shown), arranged upon a surface vessel or upon the shore as the 35 nature of the work being operated upon requires, the said pipes being, of course, controlled by suitable valves (not shown) controlling the passage of air, water, or steam through the pipes 21, 21', and 24.

40 In operation, the pipe 3 is first adjusted into close relation with the work being operated upon, this may be done by divers, or operators working from the deck of a surface vessel, or from the bank of the 45 water's edge. The valve controlling the passage through the pipe 21 is then opened so as to admit air, water, or steam, as the case may be, into the annular passage 11, from which it escapes through the opening 50 formed by and between the ring 13 and the upper end of the sleeve 7. The air, water, or steam, thus escaping from the annular space 11, naturally seeks an upward passage and has a tendency to suck in any and 55 all materials within the sphere of the lower end of the sleeve 7, thus lifting the materials being operated upon and delivering them from the upper end of the pipe 1.

I have found from actual experience that 60 when air under pressure, or water, or steam is forced into the lower end of an elevating tube, that the materials within the immediate sphere of the lower end of the elevating tube, or the mouth of the nozzle, will 65 be elevated together with the water drawn

into the tube. This has been demonstrated in the salvage of sunken coal barges and ships; and by my construction, it will be seen that, by the arrangement of the pipes 21 and 21' and their connections with the 70 annular spaces 11 and 21, the suction end of the pipe 1 may be readily inserted into various portholes or channels of a vessel without necessitating the several adjustments such as are now required in the manipulation of other submarine dredging 75 tubes.

In excavating river beds or vessels large objects often clog or choke the lower end of the suction pipe, and in this event the 80 valve controlling the lifting medium passing through the pipe 21 is turned off and the valve controlling the passage through the pipe 21' is then opened so as to force the lifting medium (air, water, or steam), 85 out through the passage 15 at the lower end of the sleeve 7 to thus force the clogging medium away from the lower end of the nozzle. After this has been accomplished, it will be understood that the valve controlling the passage through the pipe 21' 90 is turned on so as to repeat the operation of elevating the material through the elevating pipe and its connections, as herein-before described.

95 It will be appreciated that the Babbitt metal or other packing material arranged between the rings 8 may be supplied through a pipe 10', (Fig. 3), and the opening into which the pipe is screwed may be 100 afterward plugged as is done in the usual mechanical way. While I have not shown any special means for the introduction of the packing between the rings 8, it is obvious that any method such as would suggest 105 itself to any mechanic may be employed in the introduction of the packing between the rings of my present device.

110 It will thus be seen that I provide an apparatus whereby a lifting element is introduced at the lower end of the conveying tube so that an elevating action is affected upon the materials being operated upon. Also, that I provide an arrangement whereby materials which may tend to clog the lower 115 end of the nozzle may be readily displaced so that when the elevating medium is again introduced into the lower end of the tube, the materials thus displaced may be readily drawn into and forced up through the elevating pipe. It is well known in submarine dredging operations that the intake end of a suction pipe often becomes clogged and that it is necessary to send a diver down to release the obstruction at the lower end 120 of the tube. However, by my arrangement of the introduction of the elevating means into the lower end of the tube so as to discharge through the said intake end and thence to direct the elevating medium to 125 130

ward the upper or outlet end of the tube, I not only provide an arrangement operable from the surface end of the elevating tube whereby to conduct such operations 5 without the use of a diver's service, but also an arrangement whereby the work may be greatly accelerated. It will be understood that by the introduction of air, water or steam, into the lower end of the elevating 10 tube that I not only provide an elevating medium which is introduced into the lower end of the tube, but also an arrangement whereby an elevating action is produced, so that the introduction of the elevating influence will tend to force the materials 15 being dredged up through the tube.

It is obvious that various minor changes of construction and arrangement of parts may be made in my invention over the 20 details shown and described, and I distinctly desire it understood that I do not confine my invention to such minor details as those shown in the drawings, nor do I desire to be limited to the specific details as herein 25 described since the broad idea of my invention pertains to the arrangement of an apparatus whereby a lifting medium is introduced into the lower end of a so-called suction tube, combined with an arrangement 30 for dispelling objects which may tend to clog the lower end of the tube, the arrangement being such that the elevating medium may be readily shut off and conducted toward the mouth of the tube whereby to dis- 35 pel any object tending to clog the mouth of the tube.

What I claim is:—

1. In dredging apparatus, an elevating tube, a sleeve arranged in the lower end 40 thereof and connected thereto providing upper and lower annular spaces, said spaces communicating with the upper and lower ends of the elevating tube, respectively, substantially as specified, and means for conducting fluid under pressure to said spaces.

2. In dredging apparatus, an elevating tube having a sleeve arranged at its lower end and secured thereto, means interposed 50 between the ends of the sleeve whereby to cut off communication between the upper and lower ends thereof thereby providing annular spaces between the said tube and the said sleeve at the upper and lower ends of the latter, rings arranged adjacent to the 55 upper and lower ends of said sleeve, and means for conducting fluid under pressure

to the spaces formed by and between the said tube and said sleeve, substantially as and for the purpose specified.

3. In dredging apparatus, an elevating 60 tube, a sleeve arranged in the lower end of said tube, said sleeve being of less diameter than said tube, rings for locking said sleeve to said tube, said rings being arranged intermediate the length of said sleeve, a pack- 65 ing arranged between said rings whereby to cut off communication between the upper and lower spaces or channels thus formed by and between said sleeve and said tube, rings arranged adjacent to the upper and lower ends of said sleeve, said rings being carried by said tube, and means for conducting fluid under pressure to said spaces formed by and between the said tube and the 70 said sleeve. 75

4. In dredging apparatus, an elevating tube having a sleeve arranged in its lower or suction end, rings to which said sleeve is held providing upper and lower annular spaces or channels, rings carried by said 80 elevating tube and arranged adjacent to the upper and lower ends of said sleeve, said rings providing annular outlets from the spaces formed by and between the first-men- 85 tioned rings, and means to supply fluid under pressure to said annular spaces, substantially as and for the purpose specified.

5. In dredging apparatus, an elevating tube having a sleeve arranged at its lower or suction end, rings to which said sleeve 90 is held providing upper and lower annular spaces or channels, rings carried by said elevating tube and arranged adjacent to the upper and lower ends of said sleeve, said rings being adjustably connected to said ele- 95 vating tube.

6. In dredging apparatus, an elevating tube having a nozzle at its lower end, said nozzle comprising an inner sleeve connected to the lower end of said tube, rings 100 through which said sleeve is connected to the lower end of said tube providing upper and lower spaces or channels, and means for supplying fluid under pressure to said spaces or channels, substantially as and for the 105 purpose specified.

In testimony whereof I have hereunto set my hand this 20th day of June, A. D. 1918.

FREDERICK WILLIAM EBELING.
